CLAIM

The ornamental design for a combined weed remover and
hoe, as shown.

DESCRIPTION

FIG. 1 is a front elevational view of a combined weed
remover and hoe embodying my new design;

FIG. 2 is a side elevational view thereof with the opposite
side being a mirror image;

FIG. 3 is a rear elevational view thereof; and,

FIG. 4 is a perspective view thereof showing the tubular
structure detached from the footrest.

The handle is shown broken away and the tubular attachment
is shown detached in FIG. 4 for clarity and ease of
illustration.
